UNITED STATES PATENT OFFICE

150,160

DESIGN FOR A CONTAINER FOR ADHESIVE
TAPE OR THE LIKE

Hubert I. Salsbury, Los Angeles, Calif.

Application September 30, 1946, Serial No. 133,651

Term of patent 14 years

(Cl. D58—13)

To all whom it may concern:

Be it known that I, Hubert I. Salsbury, a citizen of the United States, residing at Los Angeles, in the county of Los Angeles, State of California, have invented a new, original, and ornamental Design for a Container for Adhesive Tape or the like, of which the following is a specification, reference being had to the accompanying drawing, forming part thereof, in which:

Fig. 1 is a perspective view of a container for adhesive tape or the like, showing my new design;

Fig. 2 is a side elevational view;

Fig. 3 is a top plan view;

Fig. 4 is an end elevational view; and

Fig. 5 is a bottom plan view thereof.

I claim:

The ornamental design for a container for adhesive tape or the like, as shown.

HUBERT I. SALSBURY.
